UNITED STATES PATENT OFFICE.

MICHAEL BOGRE, OF DETROIT, MICHIGAN.

ROTARY PUMP.

Application filed June 9, 1924. Serial No. 718,746.

To all whom it may concern:

Be it known that I, MICHAEL BOGRE, a citizen of the United States, residing at Detroit, in the county of Wayne and State of Michigan, have invented certain new and useful Improvements in Rotary Pumps, of which the following is a specification, reference being had therein to the accompanying drawings.

10 This invention relates to pumps or compressors of the type wherein a cylindrical casing houses an eccentric provided with a winged strap, the wing of which reciprocally oscillates in a chamber lateral to the main chamber of the pump and the strap moves in rotary contact with the inner circumferential wall of the cylinder, whereby upon the rotation of the eccentric progressively and inversely varying chambers are 20 provided on opposite sides of the said wing.

This form of pump as heretofore constructed, has offered difficulties in packing the eccentric strap in order to prevent or reduce losses due to leakage from one chamber to the other, and the objects of this invention are, therefore, to provide a form of packing and a method of adjustment of the strap whereby the same may be better fitted within the casing and whereby wear 30 between the contacting surfaces may be taken up.

A further object is to provide for the efficient lubrication of such surfaces subjected to wear, and a still further object is to provide for a positive closing off of communication between the inlet and the interior chambers of the pump during the movement of the strap following the completion of one cycle of operation and prior to the commencement of the following cycle.

In carrying the said invention into effect, I may provide in a device of the type referred to a winged strap having lateral outwardly and resiliently pressed winged packing rings and a split eccentric, part of which eccentric is movable and adapted to be adjustably spaced from the fixed part thereof to increase the throw of the eccentric whereby the throw of the strap may be 45 accordingly increased to effect adjustment of or take up wear between the said strap and its surrounding casing, the wing of the strap extending into an oscillating valve member and having an inlet duct therein 50 which terminates at a desired distance from said strap, whereby said duct will be closed

by said valve member when the said strap assumes a position adjacent the said valve member. All of which is more particularly described and ascertained hereinafter, by 60 way of example, having reference to the accompanying drawing, wherein—

Figure 1 is a sectional elevation of a pump embodying said invention;

Figure 2 is a transverse section of the 65 same;

Figure 3 is a section on the line 3^x—3^x of Figure 2;

Figure 4 is a perspective view of the winged eccentric strap removed, and 70

Figure 5 is a detail perspective view of one of the packing rings removed.

Similar characters of reference indicate similar parts in the several figures of the drawing.

1 is a pump casing comprising a body portion 2 and a cover plate 3 secured thereto by pins 4, the said casing incorporating a cylinder having a smaller communicating cylindrical chamber 5, the latter housing an 80 oscillating valve member 6 slotted as at 7 and having a lateral inlet orifice 8 communicating with an inlet 9 in the casing.

10 is a driving shaft journaled in the parts 2 and 3 of the casing and having an eccentric 11 mounted thereon which eccentric is surrounded by an eccentric strap 12 provided with a wing 13 which extends into the orifice 7 of the oscillating valve member 6, the said strap co-acting with the outer 90 wall of the casing so that two chambers —a— and —b— are provided on opposite sides of the wing 13 which chambers vary in inverse relative capacity as the eccentric rotates thereby effecting a pumping operation in the manner well known in the art.

14 is an inlet duct on one side of the said strap and 15 an outlet from the chamber —b— on the opposite side of the said strap. 16 is a non-return check valve seated in the 100 said outlet.

It is desirable that the strap 12 be adjustable with respect to the peripheral wall of this casing in order to prevent leakage between the chambers —a— and —b—, and this I effect by varying the throw of the eccentric 11 which in this case comprises a fixed part 11^a and a radially movable segment 11^b, the complete eccentric being of somewhat smaller diameter than the internal 110 diameter of the strap to allow of axial variation between the said eccentric and strap

when adjustment is being made, 17 being tapered threaded pins entering between the parts 11^a, 11^b and adapted to adjustably effect the spacing of the said part 11^b from the part 11^a to accomplish the desired result. It will be apparent that peripheral wear of the strap, or of the coacting wall of the casing may readily be taken up by entering the tapered pins 17 further into the strap.

10 Lateral packing of the strap is effected by the use of winged rings or plates 18 accommodated in correspondingly shaped recesses 19 in the sides of the said strap 12 and wing 13 thereof, these plates being outwardly pressed against the sides of the casing by springs 20 accommodated in transverse chambers 21 in the said strap; and to secure efficient lubrication of the internal parts of the pump I propose to provide the 20 said chambers 21 with oil disks 22 leading thereto from the bore of the eccentric and communicating with ducts 23 and 24 in the eccentric and shaft.

Where compressible fluids, such as air, 25 are pumped by the device there would ordinarily be a tendency of the fluid in the chamber exerting a back pressure through the inlet when the strap is in an intermediate position between the completion of each 30 stroke, namely, when the said strap is oscillating in its closest positions to the member 6 as at such times the outlet 15 would be open to the entire space around the said strap, this position being indicated in dotted 35 lines in Figure 2. To overcome this objection the inlet duct 14 terminates at a short distance from the strap and forms a closure 25 which enters the oscillatory member 6

thereby effectually cutting off, for the time being communication between the inlet and outlet orifices.

This invention may be developed within the scope of the following claims without departing from the essential features of the said invention and it is desired that the specification and drawing be read as being merely illustrative and not in a limiting sense except as necessitated by the prior art.

What I claim is:—

1. In a device of the class described, a winged strap, an oscillatory valve member entered by the wing of said strap, said wing having an inlet duct therein, and a closure shutting off communication through said duct when said strap is in its most adjacent relation to said valve member.

2. In a device of the class described, a winged strap, an oscillatory valve member entered by the wing of said strap, said wing having an inlet duct in one side thereof and said oscillatory member provided with a lateral inlet orifice communicating therewith, and a closure at the upper end of said duct extending radially beyond the periphery of said winged strap and adapted to enter said oscillatory valve member and shut off communication through said duct as the said strap closely approaches and recedes from said oscillatory member.

In testimony whereof I affix my signature 70 in presence of two witnesses.

MICHAEL BOGRE.
